THE BOSTONIAN

UNITED STATES PATENT OFFICE.

DANIEL G. STEINECKE, OF NEW YORK, N. Y.; SAMUEL STEINECKE AND WILLIAM STEINECKE ADMINISTRATORS OF SAID DANIEL G. STEINECKE, DECEASED.

ELECTRIC DENTAL FURNACE.

No. 820,025.

Specification of Letters Patent.

Patented May 8, 1906.

Application filed May 23, 1905. Serial No. 261,783.

To all whom it may concern:

Be it known that I, DANIEL G. STEINECKE, a citizen of the United States, residing at New York, in the county of New York and State of New York, have invented certain new and useful Improvements in Electric Dental Furnaces, of which the following is a specification, such as will enable those skilled in the art to which it appertains to make and use the same.

This invention relates to electric dental furnaces, and is an improvement on that specifically known as the "Hammond" electric furnace; and the object of this invention is to provide a dental furnace, as hereinafter described and claimed, in which porcelain inlays or dental work of other kinds and classes may be brought to a high degree of temperature for baking or other similar purposes, a further object being to provide an electric furnace of this class in which the muffle is composed of two parts and is readily detachable from the furnace proper, and a still further object being to provide a muffle for furnaces of this class the two parts of which may be electrically energized singly or together.

The invention is fully disclosed in the following specification, of which the accompanying drawings form a part, in which the separate parts of my improvement are designated by suitable reference characters in each of the views, and in which—

Figure 1 is a front elevation of an electric dental furnace constructed according to my invention; Fig. 2, a plan view thereof on the line 2 2 of Fig. 1 and showing diagrammatically a method of electrical connection; Fig. 3, a partial section on the line 3 3 of Fig. 1 and showing the mechanical construction of my muffle; Fig. 4, a section of the furnace proper, taken on the line 4 4 of Fig. 3; Fig. 5, a view similar to Fig. 4, but taken on the line 5 5 of Fig. 3; and Fig. 6, a detail view of the muffle which I employ.

In the drawings forming part of this specification I have shown a casing *a*, provided with a non-conductive top *b*, said top being composed of slate, marble, or other similar and suitable material, and mounted on the top *b* and at one side thereof is a furnace-casing *c*, which is secured to the top *b* by

means of screws, bolts, or in any other suitable manner.

Pivoted on the top *b* and as shown at *b*² is a rheostat-arm *b*³, adapted to engage one of a plurality of contacts *b*⁴, connected in the usual manner by means of resistance-coils, said resistance-coils being shown at *b*⁵ in Fig. 1 and being indicated diagrammatically at *b*⁶ in Fig. 2, and adjacent to the rheostat-arm *b*³ is a knife-switch *b*⁷, which is in permanent communication with a binding-post *b*⁸, to which one wire of a main electric circuit is adapted to be connected, and the spring-contacts of the knife-switch are in electrical communication with the rheostat-arm *b*³ through the resistance by means of an electrical conductor *b*⁹.

The furnace *c* comprises two vertical members *c*² and *c*³, which are connected with each other by means of a horizontal casing *c*⁴, open at its top, and resting in the upper open end of the casing *c*⁴ is a cylinder *c*⁵, which is filled with refractory material, as shown at *c*⁶, said cylinder *c*⁵, as well as the material *c*⁶ therein, extending entirely from one member *c*² to the other member *c*³ of the furnace, and the refractory material, as shown at *c*⁶, is of the form known as "fire-brick" and closely engages the cylinder *c*⁵ at the ends thereof; but in practice I prefer to provide an air-space *c*⁷ between the cylinder *c*⁵ and the fire-brick *c*⁶, as is clearly shown in Fig. 3, and arranged centrally of the fire-brick *c*⁶ is a segmental opening *c*⁸, in which is mounted a muffle *d*.

The front member *c*² of the furnace *c* is provided with an opening *e*, which registers with the opening *c*⁸ in the fire-brick *c*⁶, and said opening *e* is adapted to be closed by means of a pivoted cover *e*², provided with a peep-hole *e*³, and said pivoted cover *e*² when in a closed position rests on a shelf *e*⁴, formed on the front member *c*² of the furnace, and by means of this construction it will be seen that the muffle *d* may be withdrawn from the opening *c*⁸ through the opening *e* whenever desired.

The muffle *d*, as clearly shown in Fig. 6, is comprised of an upper member *d*² and a lower member *d*³, the lower edges of the segmentally-formed upper member *d*² being formed to engage the upper edges of the horizontally-ranging member *d*³, and the members *d*² and *d*³ of the muffle *d* are each provided with in-

dependent windings of conductive material, as shown at d^4 and d^5 , respectively, the ends of the winding d^4 being provided with terminal plates d^6 and d^7 , and the ends of the winding d^5 being provided with terminal plates d^8 and d^9 , as clearly shown in Figs. 4 and 5.

Adjacent to and adapted to make contact with the terminal plates d^6 and d^8 , as shown in Fig. 4, is a terminal plate e^6 , which is connected to a contact e^6 , secured in the fire-brick c^6 by means of an electrical conductor e^7 , and mounted in the fire-brick c^6 at points adapted to make contact with the terminal plates d^7 and d^9 are terminal plates e^8 and e^9 , which are in electrical connection with contacts f and f^2 by means of electrical conductors f^3 and f^4 , respectively, and the contacts e^6, f , and f^2 are insulated from the cylinder c^6 , in which they are mounted, by means of the fire-brick or refractory material c^6 , and it will be seen by means of this construction that when the muffle d is in position for use the forward terminals of the windings d^4 and d^5 are both in electrical communication with the contact e^6 , whereas the rearward terminals of the said windings are in electrical communication with independent contacts, respectively.

30 Mounted on the top b of the casing a and passing through the casing c^1 of the furnace c are three tubes g , g^2 , and g^3 , in each of which is a rod g^4 , which is insulated from the tubes g , g^2 , and g^3 , as clearly shown in the drawings, and the rods g^4 are each provided with contacts g^5 at their upper ends, the contacts g^5 of the rod g^4 in the tube g making electrical connection with the contact e^6 , whereas the contacts g^5 of the rods g^4 of the tubes g^2 and g^3 are 35 in electrical connection with the contacts f and f^2 , respectively, when the cylinder c^6 is in position.

In Fig. 2 of the drawings I have shown the tubes g , g^2 , and g^3 in section, as well as the rods g^4 , mounted therein, and I have also shown diagrammatically the electrical connections of the parts just described, and also in electrical communication with the contact g^5 of the tube g^3 is a switch h , which is adapted 40 to make electrical connection with the contact g^5 of the tube g^2 by means of a terminal h^2 , and the switch h is in communication with a binding-post h^3 by means of an electrical conductor h^4 , and said binding-post serves as 45 the electrical connection for the other wire of the main electric circuit, and it will be seen that when the parts are in the positions shown in Fig. 2 the current passes from the binding-post h^3 through the knife-switch b' , 50 rheostat and rheostat-arm b^2 , rod g^4 of the tube g through the winding d^5 to the contact g^5 of the tube g^3 , and thence to the switch h through the electrical conductor h^4 to the binding-post h^3 , and the circuit is completed 55

through the bottom member d^3 of the muffle d , and said member is accordingly heated.

When the switch h is moved to the left into engagement with the terminal h^2 , the current passes as just described and also passes through the winding d^4 to the contact g^6 of the tube g^2 , and thence to the terminal h^2 and through the switch h and to the binding-post h^3 , and the upper member d^2 of the muffle is thereby heated, and it will be seen that the switch h therefor controls the energizing of 70 the winding d^4 of the upper member d^2 of the muffle, it being frequently necessary or advisable in the making of porcelain inlays to have all the heat at the bottom thereof, but none above the same, as it has been found 75 that better results are produced in this manner than when both the upper and lower surfaces of the muffles are heated.

It will also be seen that the muffle d may be removed from the fire-brick c^6 at any time 80 for substitution or repair, and if the wiring at any time should project through the inner surface of the muffle all that is necessary is to remove the same, separate the members thereof, and embed the loose winding or portion thereof and replace the muffle, and it will be also apparent that any method of electric wiring for accomplishing the results herein specified and intended may be provided, and the arrangement of the parts of my apparatus as shown may be varied, and various other changes in and modifications of the construction herein described may be made 85 without departing from the spirit of my invention or sacrificing its advantages.

Having fully described my invention, what I claim as new, and desire to secure by Letters Patent, is—

1. In a furnace, a base having electric contacts forming terminals of an electric circuit, standards secured to the base, a casing open at its top between said standards, a metal cylinder resting in the open end of said casing, said cylinder being filled with refractory material and said refractory material being provided with a central opening, a muffle in said central opening and an electric heating-circuit in the walls of said muffle and terminating in electric contacts to complete the circuit with the source of electricity of 105 making electrical connection with the said electric contacts of the base, substantially as shown and described.

2. In a furnace of the class described, a base, contacts forming terminals of an electric circuit on said base, vertical standards on said base, a casing open at its top and connecting said standards, an oven of refractory material resting in the open end of said casing and an electric heating-circuit arranged 110 in said oven and in electrical communication with said terminals of said electric circuit, substantially as shown and described.

3. In a furnace, a base, vertical standards secured thereto, a casing open at its top and connecting said standards, a cylinder filled with refractory material resting in the open top of said casing, said refractory material being provided with a central segmental opening, a muffle detachably mounted in said opening, said muffle being composed of an upper and lower member, an electric heating-circuit arranged in the walls of said upper member, an electric heating-circuit arranged in the walls of said lower member, and means for energizing said electric heating-circuits, substantially as shown and described.
4. In a furnace, a base, vertical standards secured thereto, a casing open at its top and connecting said standards, a cylinder filled with refractory material resting in the open top of said casing, said refractory material being provided with a central segmental opening, a muffle detachably mounted in said opening, said muffle being composed of an upper and lower member, an electric heating-circuit arranged in the walls of said upper member, an electric heating-circuit arranged in the walls of said lower member, and means for energizing said electric heating-circuits independently of each other, substantially as shown and described.
5. A heater, comprising a muffle composed of two detachably-connected parts, an electric heating-circuit in the walls of one of said parts, an electric heating-circuit in the walls of the other of said parts, and means for energizing said circuits independently of each other, substantially as shown and described.
6. In a furnace, a muffle composed of an upper and lower member, an electric heating-circuit arranged in the walls of the upper of said members, an electric heating-circuit formed in the walls of the lower of said members, the terminals of said electric heating-circuits being connected at one end and being provided with independent contacts at the other end, and devices communicating with said terminals and contacts for completing an electric circuit through said electric heating-circuits, substantially as shown and described.
7. In an electric heater of the class described, a casing of refractory material provided with an opening therein, a muffle in said opening and removable therefrom, said muffle being composed of independent members having independent heating-circuits, substantially as shown and described.
8. An electric heating-furnace provided with a muffle composed of separate detachable top and bottom parts, having independent circuits, substantially as shown and described.
9. An electric heating-furnace provided with a muffle composed of top and bottom parts, and means for heating either or both of said parts separately, substantially as shown and described.

In testimony that I claim the foregoing as my invention I have signed my name, in presence of the subscribing witnesses, this 18th day of May, 1905.

DANIEL G. STEINECKE.
